[57] CLAIM

The ornamental design for a motorcycle front fender, as
shown and described.

DESCRIPTION

FIG. 1 is a front view of a motorcycle fender according to
my new design;FIG. 2 is a left side elevational view thereof, the right side
being a mirror image of that shown;

FIG. 3 is a rear view thereof;

FIG. 4 is a top plan view thereof; and,

FIG. 5 is a bottom plan view thereof.

The broken lines shown in FIG. 2 drawing view are for
illustrative purposes only and form no part of the claimed
design.
